UNITED STATES PATENT OFFICE.

FERNAND FOREST, OF SURESNES, FRANCE:

INTERNAL-COMBUSTION ENGINE.

1,015,948.

Specification of Letters Patent. Patented Jan. 30, 1912.

Application filed September 20, 1910. Serial No. 582,846.

To all whom it may concern:

Be it known that I, FERNAND FOREST, a citizen of the French Republic, residing at 40bis Rue Jean-Jacques Rousseau, Suresnes, 5 Seine, France, have invented certain new and useful Improvements in Internal-Combustion Engines, of which the following is a specification.

This invention relates to the application 0 to internal combustion engines of an explosive mixture distributor, having a short stroke and large ports, which is independent of the movement of the piston, and moves in the interior of the cylinder, in the upper 5 part of the latter.

The invention relates likewise to a special mode of constructing the head of the cylinder, for the purpose of enabling the distribution to be applied and protecting the latter from the excessively violent effects of the 0 explosion.

With this system of distribution a single cam is employed for controlling the admission and the exhaust for each cylinder.

5 The accompanying drawings illustrate a form of the invention in the case of a multi-cylinder engine, (the drawing showing only one cylinder of the engine).

Figure 1 is a vertical section of the cylinder. Fig. 2 is a partial vertical section (perpendicular to the preceding one) of the upper part of the cylinder. Figs. 3 and 4 are a plan and an elevation respectively of the distributor. Figs. 5, 6, 7, and 8 are dia- 30 grammatic illustrations of the position of the distributor at the commencement of each of the strokes of the four stroke cycle.

In these drawings 1 is the cylinder, comprising a water-jacket 2. The cooling water 40 circulates in the usual manner, in the spaces 3. As will be seen particularly from Fig. 1, the upper portion of the cylinder is bored with a larger diameter in the part 45 *a b*. This part is intended to receive the distributor 5 which is about to be described.

The cylinder 1 is closed at the top by the head 6 completed by the cover 7, as will be mentioned hereafter. In this head 6 a chamber 3' is formed for the circulation of 50 the cooling water.

The distributor 5 which is illustrated separately in Figs. 3 and 4 consists of an annular ring, the external diameter of which is that of the cylinder 1 in the part *a b*, and its interior area exactly that of the ring 1 in the 55 part intended for receiving the piston.

Over a portion of the diameter of the cylinder that forms the distributor is a cross-piece 5' forming part with the actual distributor 5 and with its controlling rod 5''. 60 In the cylinder head 6 a chamber 8 is diametrically arranged, which is intended for receiving the cross-head 5' of the distributor.

In order to mount the distributor, the rod 65 of the latter is introduced into the sleeve 6' of the head 6, which is easily effected, the head being detached from the cylinder and the cover 7 removed. Of course the distributor is arranged in such a manner that the cross-head 5' comes into the recess 8 in 70 the head. The cover 7 the exterior diameter of which is that of the interior of the cylinder and is fixed to the head by screws 9, can then be put on. The cover 7 is provided on its circumference with a segment 75 10 for insuring tightness. Nothing thus remains but to mount the head on the cylinder in the ordinary way, an operation which is effected very easily, the distributor occupying its seating *a b*. As will be seen from 80 Figs. 1 and 2, the crosshead 5' of the distributor is inclosed, after this mounting has been effected, in the recess 8 formed in the lower part of the cover 7. The dimensions of these parts are determined so that a small 85 space is left between the lower face of the cross-head 5' and the upper face of the cover 7. In this manner the effects of the explosion acting on the cover 7 are not transmitted to the cross-head 5' of the distributor. 90

In the lower part of the distributor 5 a certain number of extended openings are formed. Corresponding openings 12-13 are formed in the cylinder 1. The opening 12 in the cylinder serves for the admission 95 of the carbureted mixture entering through the pipe 14. The opening 13 serves for the discharge of the exhaust gases through the pipe 15. The openings 12 and 13 are not placed at the same level. In these circumstances it is easy to understand that, accordingly as the distributor 5 has reached a higher or lower point in its course, the openings 11, in the said distributor come opposite the admission opening 12 or the exhaust 100 opening 13 of the cylinder, or opposite a solid part of the cylinder. In this latter case, the cylinder is closed (during compression and working).

The displacement of the distributor for 110 each cylinder is controlled by a single-cam 16 which, in the case of multi-cylinder mo-

tors, is placed at the top of the cylinders, and, in the case of single cylinder motors is mounted in the lower part, and is driven at half the speed of the crank shaft. The rod 5 of the distributor is connected with the lever 17 that pivots around the shaft 18 and which carries at its other end a roller 19 pressed against the cam 16 by the spring 20. As the cam 16 rotates in the direction of the arrow *f* it is easy to understand that when it occupies the position shown in Fig. 5, the admission is about to begin, the openings 11 in the distributor coming opposite the orifice 12 in the cylinder. The admission continues 10 as long as the part E—A of the cam is passing over the roller 10. As the cam continues rotating, the part A—C passes over the roller, and the distributor is in the position shown in Fig. 6. In this position the admission and exhaust openings are closed. The cylinder thus is closed and the gases are compressed. When the compression is ended, the ignition is effected in the usual manner by the sparking plug 21 (or by any 15 other igniting device) and the explosion takes place. During the third phase the cam rotates from C to T. The openings 12 and 13 are covered during this third phase (Fig. 7). Finally, when the piston is at the 20 lowest point of its course and is about to ascend (fourth phase-exhaust) the part T. E of the cam 16 passes over the roller 19 and the distributor takes the position shown in Fig. 8. In this position the opening 13 is opposite the corresponding opening 11 in the distributor and consequently, the cylinder is placed in communication with the exhaust pipe. The exhaust gases can then be 25 discharged, and a new cycle begun.

40 As will be seen, the application of the distributor forming the subject matter of the invention, enables the values usually employed in explosion motors to be dispensed with, and only requires for controlling it, a single cam, which effects the admission and the exhaust by means of a very powerful and extremely simple mechanical device.

What I claim and desire to secure by Letters Patent is:—

50 1. In internal combustion engines, in combination, a cylinder comprising an upper portion of larger diameter than the normal bore of the cylinder, said cylinder being provided with inlet and outlet ports communicating with said enlarged upper portion, an annular distributor reciprocatingly mounted

within said enlarged upper portion and provided with openings adapted to move into and out of registry with said ports depending upon the position of the distributor relative to the cylinder, means operatively connected to said distributor and actuated by the engine for reciprocating said distributor, and means for protecting said last mentioned means from the effects of the explosion of the gases within the cylinder. 60

2. In internal combustion engines, in combination, a cylinder comprising an upper portion of larger diameter than the normal bore of the cylinder, said cylinder being provided with inlet and outlet ports communicating with said enlarged upper portion, an annular distributor reciprocatingly mounted within said enlarged upper portion and provided with openings adapted to move into and out of registry with said ports depending upon the position of the distributor relative to the cylinder, a crosshead, means operatively connected with said crosshead and actuated by the engine for reciprocating said distributor, and means positioned within said cylinder to protect said crosshead from the effects of the explosion of the gases within the cylinder. 70

3. In internal combustion engines, in combination, a cylinder comprising an upper portion of larger diameter than the normal bore of the cylinder, said cylinder being provided with inlet and outlet ports communicating with said enlarged upper portion, an annular distributor reciprocatingly mounted within said enlarged upper portion and provided with openings adapted to move into and out of registry with said ports depending upon the position of the distributor relative to the cylinder, a crosshead, means operatively connected with said crosshead and actuated by the engine for reciprocating said distributor, said cylinder being provided with a head having a groove within which said crosshead is adapted to reciprocate and a cover secured to the inner surface of said head and extending over said groove whereby said crosshead will be protected from the effects of the explosion of the gases within the cylinder. 80

In testimony whereof I have affixed my signature, in presence of two witnesses.

FERNAND FOREST.
